MAIL BOX

William Carl Luss, Hamburg, N. Y.

Application August 12, 1935, Serial No. 35,866

1 Claim. (Cl. 232—33)

The invention relates to a mail box and more especially to rural delivery mail boxes for letters and packages.

The primary object of the invention is the provision of a mail box of this character, wherein the front door is swingingly supported and carries a gate for a slot therein through which is passed mail matters such as letters or the like for deposit within the box while the door when opened will allow packages or the like to be placed within the box, the gate for the slot being constructed for the reception of paper and coin money which is procurable to a collector of mail, the gate being of novel construction.

Another object of the invention is the provision of a box of this character, wherein the construction thereof is novel in form so that letters or the like and money can be carried at the front and upon the front door of the box to have the same readily accessible to a collector of mails while the box will form a depository for letters and packages for either incoming or outgoing mail matter, the box being adapted for rural mail service.

A further object of the invention is the provision of a box of this character, which is simple in construction, reliable and efficient in its operation, neat in appearance, adapted for various kinds of incoming and outgoing mail matter, strong, durable and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a fragmentary perspective view of a mail box constructed in accordance with the invention showing by full lines the front door in open position and by dotted lines said door closed.

Figure 2 is a fragmentary longitudinal vertical sectional view through the box the latter being on an enlarged scale.

Figure 3 is a sectional view on the line 3—3 of Figure 2 looking in the direction of the arrows.

Figure 4 is a fragmentary vertical longitudinal sectional view showing a slight modification.

Similar reference characters indicate corresponding parts throughout the several views in the drawings.

Referring to the drawings in detail, the box constituting the present invention comprises a body, a portion thereof being indicated at A,

closed at its bottom, sides, top and one end while the opposite end is opened and is adapted to be closed by a front door B. The body and the door are preferably made from sheet metal and the top of said body may be of any desirable shape, in this instance it being of arcuate form.

The door B is formed with a marginal rim 10 which extends along the sides and uppermost or outermost edge thereof while the lowermost or innermost edge with relation to the body A 10 is devoid of a rim. This door B has provided therein a slot 11 through which is placed mail matter such as letters or the like for deposit within the body A of the box.

Fixed to the inner face of the door are hinges 12 12 the pintle 13 therefor being fitted in pintle sleeves 14 carried at the lowermost edge of the open front end of the body A, the hinges 12 being removed from the innermost or lowermost edge of the door B so that this innermost or lowermost edge of the door when swung to open position will underlie the bottom of the body A at its open front and thus the door will be held in a substantially horizontal position to constitute a rest or shelf when opened. The rim 10 25 has struck therefrom frictional latching nibs 15 which engage in seats or notches 16 provided in the sides of the body A so that the said door B can be latched in the full open position thereof as is clearly shown in Figure 1 of the drawings. 30 The door B at its uppermost portion carries a spring snap latch 17 cooperating with a spring snap keeper 18 secured to the top of the body A, the latch and the keeper being formed with spring openings 19 which match with each other on the closing of the door to accommodate a suitable lock for the fastening of the door or the securing thereof in its closed position.

On the pintle 13 for the hinges 12 is a coiled tensioning spring 20 which has fixed connections 40 at 21 and 22 with the door B and bottom of the body A, respectively. This spring functions to swing the door automatically to closing position on unlatching the door by freeing the nibs 15 from the seats 16. When the door is closed the 45 rim 10 telescopes over the body A to render the joint between said door and body weatherproof.

Carried at the inner face of the door B is a pair of spring clips 23 to constitute holders for letter contained envelopes, one being indicated 50 at 24 therein.

Closing the slot 11 is a gate or flap including the angularly bent portions 25 and 26, respectively, the latter having a marginal rim 27 to provide a money tray 28 at one face thereof while 55

the portion 25 at the inner face thereof is constructed with a change pocket 29. This portion 25 is adapted to close the slot 11 and the gate or flap is supported upon a hinge pintle or pivot 30 having its ends journaled in bearings 31 fitted to the inner face of the door B. The tray 28 has therein a weight 32 which functions to urge the flange 33 of the portion 25 against the inner face of the door B so that the flap or gate will be in closing position with respect to the slot 11. The portion 25 when moved to open position swings through the slot 11 inwardly of the door B so that mail matter 34 can be inserted through the slot 11 to be deposited within the body A of the box. The tray 28 is equipped with a paper money clip 35 for the clamping of paper money 36 therein. This tray on the opening of the door B to the horizontal position shown in Figure 1 of the drawings will rest upon the said door so that the money 36 will be readily accessible for removal from the clip 35 and the coins or change within the pocket 29 will automatically slide therefrom into the tray 28 as will be apparent from Figure 1 of said drawings. When the door is closed the gate or flap automatically adjusts itself so that the portion 25 will operate to close the slot 11 in said door. It is impossible to gain access to the interior of the box through the slot 11 except for the deposit of mail matter 34 through the slot 11 into the box. The door B is swung to open position when packages or parcel post mail matter is to be recovered from the body of the box or deposited therein.

In Figure 4 of the drawings there is shown a slight modification, wherein the coiled spring 37 is substituted for the spring 20 and this spring is connected with eye rivets 38 fixed to the door and bottom of the body, respectively, of the box. 5

What is claimed is:

A mail box of the kind described comprising a box like body permanently closed at its bottom, sides, top and one end and having an open end opposite to the latter, a door closing the open 10 end and having a flange extended along the side and top of the body, said door being provided with a transversely disposed slot for accommodating mailing matter for deposit within the body, a gate pivoted to the inner side of the door 15 at the slot and having angularly bent portions, one of said portions being provided with a marginal rim to provide a money tray, the other of said portions being formed with a change pocket and this latter portion normally closing the slot, 20 the money tray and change pocket being arranged for inaccessibility through the slot, a flange on the gate at the change pocket and engageable with the door to limit the outward swinging of said gate through the slot and a 25 weight fitted in the money tray for normally holding the flange on the change pocket of said gate contacting with the door for the closing of the slot by said gate.
